UNITED STATES PATENT OFFICE.

HERBERT L. JOHNSTON, OF TROY, OHIO, ASSIGNOR TO THE TROY CARRIAGE SUN SHADE COMPANY, OF TROY, OHIO, A CORPORATION OF OHIO.

TIP FOR UMBRELLA-RIBS.

No. 926,255.

Specification of Letters Patent.

Patented June 29, 1909.

Application filed December 9, 1908. Serial No. 468,693.

To all whom it may concern:

Be it known that I, HERBERT L. JOHNSTON, a citizen of the United States, residing at Troy, in the county of Miami and State of Ohio, have invented certain new and useful Improvements in Tips for Umbrella-Ribs, of which the following is a specification.

The invention relates to improvements in tips for umbrella ribs.

10 The object of the invention is to provide a simple and effective device for securing the fabric cover of the umbrella to the ribs in a manner which will permit the ready removal of the cover when desired but at the 15 same time effectually secure it in place when in position.

The invention consists in the constructions and combinations of parts hereinafter described and set forth in the claims.

20 In the accompanying drawings, Figure 1 is a vertical sectional view on an enlarged scale of a device embodying my invention, a portion of the cover and rib being shown in position therein. Figs. 2 and 3 are perspective views of parts of the device. Fig. 4 is a modified form of sleeve.

Like parts are represented by similar characters of reference in the several views.

The tip consists essentially of a cap, *a*, 30 formed of sheet metal, and a sleeve, *b*, also of sheet metal. The sleeve is preferably formed of resilient nature and provided with a longitudinal slit, *b*¹, on one side and with a flaring end, *b*². The sleeve, however, may 35 be, if desired, formed of a solid non-resilient nature.

In assembling the parts, the fabric of the cover *c* is placed over the open end of the cap and the flared end of the sleeve pressed 40 into the same so that the fabric will lie between the sleeve and the cap. An internal bead, *a*¹, is then formed on the cap by pressing the metal in, as indicated in the sectional view, thus securing the fabric between the 45 sleeve and cap at this point. The distance between diametrically opposite points on the bead will preferably be slightly less than the diameter of the flared part of the sleeve so as to provide an interlocking connection between the two parts, and thus prevent the 50 sleeve from working up out of the cap or the cap from slipping off the fabric about the rib. This distance, however, might be substantially the same, or even less, the 55 thickness of the fabric between the bead and

the sleeve forming in effect an enlargement of the bead. When the bead is made in the outer cap it will cause the resilient sleeve to be contracted more or less, but when the rib, *d*, is inserted the sleeve will spring out 60 to accommodate itself to the size of the rib and also will be caused to be impinged more firmly against the bead and thus more tightly secure the fabric in position. After 65 the rib is inserted in place the head thereof will serve to hold the fabric against the bottom of the cap and draw the same taut between the head and the flared portion of the sleeve, and thus further tend to secure the 70 parts together.

When a non-resilient sleeve is employed, the fabric will be clamped securely between the bead, *a*¹, of the cap and the solid wall of the sleeve. In this case the sleeve will 75 always be made large enough to accommodate the largest size rib.

Having thus described my invention, I claim:

1. In a device of the character described, a cover, an outer cover-receiving member, an 80 inner rib-receiving member inserted therein, and an internal and external projecting portion on the respective members between which the cover lies forming an interlocking joint, substantially as specified.

2. In a device of the character described, a cover, an outer cover-receiving member open at one end, an inner open-ended rib-receiving member insertible within said outer member, said cover being located between said members an internal projecting portion on said outer member adapted to clamp the cover to the inner member, and an external projecting portion on said inner member lying within said outer member and 95 beneath the internal projecting portion thereof, substantially as specified.

3. In a device of the character described, a cover, an outer cover-receiving member open at one end, an inner open-ended rib-receiving member insertible within said outer member, said cover being located between said members said inner member being formed with a longitudinal slit and being of resilient material, an internal projecting portion on said outer member, and an external projecting portion on said inner member lying within the outer member and beneath the internal projecting portion 100 thereof, substantially as specified.

4. In a device of the character described, a cover, an outer cap, a sleeve inserted therein having a flaring end, and an internal rib in said cap above said flared end of the 5 sleeve adapted to clamp the cover to the sleeve, substantially as specified.
5. In a device of the character described, and in combination with the fabric cover and rib, of an outer cap to receive the fabric, 10 an inner sleeve adapted to be inserted inside the fabric in said cap, and also adapted to receive the rib, the outer end of said sleeve being flared, an internal bead on said cap, said cover lying between said flared end and 15 said internal bead, substantially as specified.

6. In a device of the character described, and in combination with the cover and rib, of an outer cover-receiving cap, an inner rib-receiving sleeve, said sleeve being formed of resilient material and having a longitudinal 20 slit, an internal bead formed on said outer cap, and a flared portion formed on the outer end of the sleeve beneath said bead, substantially as specified.

In testimony whereof, I have hereunto set my hand this 2nd day of December, 1908.

HERBERT L. JOHNSTON.
